UNITED STATES PATENT OFFICE.

ARTHUR C. ROWLEY, OF PHILADELPHIA, PENNSYLVANIA, ASSIGNOR TO GLOBE AUTOMATIC SPRINKLER COMPANY, OF PHILADELPHIA, PENNSYLVANIA, A CORPORATION OF PENNSYLVANIA.

SPRINKLER GUARD.

Application filed July 1, 1921. Serial No. 481,814.

To all whom it may concern:

Be it known that I, ARTHUR C. ROWLEY, a citizen of the United States, residing in Philadelphia, Pennsylvania, have invented 5 Sprinkler Guards, of which the following is a specification.

One object of my invention is to provide an open sprinkler head guard of such construction that it is necessarily applied in 10 such position that its interference with the proper functioning of such sprinkler head is an impossibility.

It is further desired to provide a relatively simple and substantial sprinkler head 15 guard which shall include means whereby it may be quickly applied or removed and shall be of such construction that it cannot be turned after it has been applied to the sprinkler head, nor can any part of it interfere with the movement of the lever arms 20 of said head so as to prevent their separation and the subsequent opening of the sprinkler valve, when said lever arms are released by the melting of the fusible link 25 whereby they are normally connected.

The invention further contemplates novel means for immovably connecting a sprinkler head and a guard therefor.

These objects and other advantageous 30 ends I attain as hereinafter set forth, reference being had to the accompanying drawings, in which,

Figs. 1 and 2 are respectively a plan and a vertical section on the line 2—2, Fig. 1, 35 illustrating my improved guard applied to a sprinkler head; and

Figs. 3 and 4 are plans of the base of the guard, showing its parts in their closed and open positions, respectively.

In the above drawings, 1 represents the threaded nipple whose upper or delivery opening is normally closed by a valve 2 and which has integral with it a yoke 3 carrying a water spreader 4. The valve 2 is normally maintained in its closed position by a pair of coacting levers 5 and 6 which engage each other and also respectively engage the valve and the top of the yoke 3, while their free arms are normally connected by a fusible or temperature-responsive link 7.

The base 8 of the yoke is substantially rectangular in outline and in accordance with my invention has clamped to it the two

parts of a guard base ring 9—9 of substantially circular outline and said parts are hinged together at one side by a suitable pintle in the form of a screw 10, having opposite said screw, projecting lugs 11 separately connected by a screw 12. 55

Each half of the base ring 9 has a diametric web portion 13 formed with a semi-circular edge recess 14 for the reception of the cylindrical neck 8^a of the nipple 1 immediately above its thread. Adjacent this opening 14 for the nipple, each of the web portions 13 has its top face recessed to more or less closely fit and immovably hold the rectangular or other-than-circular base 8 of the yoke of the sprinkler head so as to 65 keep said guard ring from turning into or being assembled in such a position as to extend under or in any way interfere with the proper functioning of the lever arms of the 70 sprinkler head. 75

The base ring 9—9 is formed with a set of inwardly extending projections 17—17 for the reception of the lowest circular member 18 of a wire guard designed to surround and protect the sprinkler from mechanical 80 injury and there is also a second set of inwardly extending projections or tongues 19 so placed on the ring 9—9 as to coact with the projections 17—17 to hold the guard in place. 85

In addition to the bottom member 18, the guard includes two other parallel circular members 20 and 21 soldered or otherwise rigidly connected to the circularly curved vertical members 22—22, each of which at 90 one end is connected to the ring 18 and at its opposite end is fastened to a small top ring 23.

In applying the guard to a sprinkler head, the two members 9—9 of the base ring are swung apart as indicated in Fig. 4 and are thereafter closed around the base 8 and neck 8^a of the head so that said base enters the depression 13^a at the central part of the web portions 13. At the same time that the two parts 9—9 are being closed around the sprinkler head, the wire guard is placed adjacent said parts so that its bottom wire 18 is engaged by and lies between the two sets of projections 17 and 19 thereof, after 100 which the screw 12 may be inserted and the parts 9—9 be rigidly connected. 105

It is particularly to be noted that the base

portion of the guard is cut away or open as indicated at 25, so it has no portion which by any possibility could be caused to project under the lower arm of the lever 6 in such manner as to prevent full downward swing of the latter occurring when the fusible link releases this arm from the co-acting arm of the lever 5. In other words, there is no possibility of relative movement 10 of the base ring 9—9 of the guard upon the sprinkler head, and even the wire portion of said guard is likewise prevented from more than relatively slight rotary movement, since the projections 19 come 15 into engagement with the curved members 22 when the latter is slightly turned in either direction.

I claim:

1. A sprinkler guard including an enclosing cage and a base consisting of two substantially flat elements hinged together, each

having a side opening and formed with an edge indentation for the reception of the nipple of a sprinkler head, the face of said base adjacent the edge recesses thereof having a depression for the non-rotatable reception of the yoke base of a sprinkler head for retaining the latter in position with its levers adjacent one of the side openings of said base. 25

2. A sprinkler guard consisting of a wire body and a base made in two parts hinged together, each of said parts having sets of inwardly projecting tongues engaging the body and having a central web defining side openings, said web having an opening for the passage of the nipple of a sprinkler head and being formed with portions for non-rotatably engaging the yoke base of the 30 35 sprinkler head.

ARTHUR C. ROWLEY.
